(57) **CLAIM**

The ornamental design for a computing device housing, as shown and described.

DESCRIPTION

FIG. 1 is a perspective view of the computing device housing showing my design;

FIG. 2 is a front view thereof;

FIG. 3 is a top view thereof;

FIG. 4 is a right side view thereof;

FIG. 5 is a bottom view thereof;

FIG. 6 is a left side view; and,

FIG. 7 is a cross-sectional view taken along line 7—7 of FIG. 2 illustrating the surface contour of the front view.

The rear of the computing device housing forms no part of the claimed design.

The broken line illustrations of an indicator, a lock and a cord outlet are not part of the design sought to be patented.
